UNITED STATES PATENT OFFICE.

WALTER L. FRY, OF NEW ROCHELLE, NEW YORK.

DESIGN FOR A COMBINED TROUSERS AND BOOTS.

55,856.

Specification for Design.

Patented July 20, 1920.

Application filed April 3, 1919. Serial No. 287,364. Term of patent 7 years.

To all whom it may concern:

Be it known that I, WALTER L. FRY, a citizen of the United States of America, residing in the town of New Rochelle, county of Westchester, State of New York, have invented a new, original, and ornamental Design for a Combined Trousers and Boots, of which the following description, in connection with the accompanying drawing, is the specification.

In the accompanying drawings—

Fig. 2 is a side view of a combined trousers and boots showing my new design.

I claim as my invention:

The ornamental design for a combined trousers and boots, as shown.

WALTER L. FRY.
